UNITED STATES PATENT OFFICE.

HARRIE A. BALLARD, OF BOSTON, MASSACHUSETTS, ASSIGNOR TO THE BOYLSTON MFG. COMPANY, OF SOUTH BOSTON, MASSACHUSETTS, A CORPORATION OF NEW JERSEY.

PRESSER-FOOT MECHANISM.

1,139,626.

Specification of Letters Patent. Patented May 18, 1915.

Original application filed August 21, 1906, Serial No. 331,529. Divided and this application filed January 28, 1909. Serial No. 474,670.

To all whom it may concern:

Be it known that I, HARRIE A. BALLARD, of Boston, in the county of Suffolk and State of Massachusetts, have invented certain new and useful Improvements in Presser-Foot Mechanism, of which the following is a specification.

This invention relates to shoe-sewing machines and more particularly to the thread-clamping mechanism and presserfoot mechanism of such machines, and the present application is a division of my application Serial No. 331,529, filed August 21, 1906, which resulted in U. S. Letters Patent 1,098,874. The presserfoot as shown is normally held upon the work by the force of a spring and is locked and unlocked automatically and is automatically raised from the work or released to permit feeding of the work. The needle thread is automatically clamped and released at appropriate intervals. Mechanism is provided for automatically unlocking and raising or releasing the presserfoot and for releasing the needle thread at the same time when the power shaft of the machine is turned in the reverse direction, to the end that the operator may quickly and easily remove the work from the machine when a sewing or stitching operation has been finished. The power shaft is provided with a hand wheel by which the operator may manually turn the shaft in the reverse direction when a sewing or stitching operation has been finished, to effect the release of the work by the presserfoot and to effect the release of the needle thread.

One form in which the invention may be embodied is illustrated upon the accompanying drawings and described in the following specification.

On the drawings, Figure 1 represents a right side elevation of a shoe-sewing machine equipped with presserfoot mechanism and thread-clamping mechanism arranged and constructed in accordance with this invention. Fig. 2 represents a vertical section through the head as seen from the left hand side. Fig. 3 represents an elevation of a fragment of the presserfoot locking mechanism as seen from the right hand side. Fig. 4 is a section on line 4-4 of Fig. 3. Fig. 5 is a detail of the mechanism for actuating the thread clamp.

The same reference characters indicate the same parts wherever they occur.

The type of machine illustrated is adapted to form a lock stitch and comprises essentially a head or frame 10, a cam shaft 11 journaled therein, and a stitch-forming mechanism including an oscillatory needle 12, an awl 13, a work rest 14, a looper 15 for the needle thread, and a shuttle, not shown, but presumably contained in a casing 16.

17 represents a presserfoot and 18 represents a carrier therefor. The said carrier is in the form of a lever, and its fulcrum is indicated at 19. The rear end of the lever 18 is connected to one end of a spring 20 of 70 which the other end is connected to a suitable fixture 21. The tension of the spring 20 is exerted at all times for the purpose of holding the presserfoot toward the work rest 14 with which it cooperates to clamp 75 the work inserted between them. The awl 13 is carried by an awl carrier 22 which is mounted upon a stud 23 about which it is adapted to oscillate in unison with the needle. The awl carrier, however, receives 80 motion toward and from the needle for the purpose of feeding the work, and for this reason the stud 23 about which it oscillates is mounted in an arm 24 carried by a carriage 25 arranged in suitable guides extending laterally or parallel to the axis of the stud 23. The means for reciprocating the carriage 25 includes a lever 26 mounted upon a fulcrum 27 and having at one end a roll 28 in co-operative engagement with a 85 cam 29 on the shaft 11. The needle 12 is affixed to a needle carrier 30 which is mounted upon a stud, not shown, about which it is adapted to oscillate. The means for actuating the needle carrier includes a 90 crank 31 on the shaft 11, and a pitman 32 connecting the crank with the needle carrier. The axis about which the needle carrier moves is in alignment with that of the awl carrier and the two carriers are connected so that they may be oscillated in 100 unison by the crank and pitman. The means for connecting the two carriers is a form of pin and slot connection, and includes a laterally extending pin 33 extending from the needle carrier into a slot 34 formed in the awl carrier. This connection provides for the independent lateral move-

ment of the awl carrier for the purpose of feeding the work without affecting the needle.

As hereinbefore stated, the spring tension, which serves to hold the presserfoot in engagement with the work, is exerted at all times, and this means that it is exerted during the feeding of the work, but when the spring tension is properly adjusted, it does not interfere with the feeding of the work. It is desirable, however, that the presserfoot should be locked so as to further insure the clamping of the work during the actuation of the stitch-forming mechanism. For this purpose, the presserfoot lever 18 is provided with a pawl 36 which is adapted to coöperate with a stationary ratchet 37 attached to the frame 10. The relation of the pawl and ratchet with the presserfoot lever is such as to prevent movement of the presserfoot away from the work rest.

Suitable means is provided for holding the pawl normally in engagement with the ratchet and for disengaging the pawl therefrom. According to the present invention this may be done in three ways. First by actuation of a handle 38, second, by means of a cam 39 mounted upon the shaft 11, and third, by means of manually reversing the direction of movement of the cam shaft. The pawl 36 is formed on one end of a member which is mounted upon two pivots 40 and 41. The pivot 40 is carried by a plunger 42 arranged so as to slide in guides 43 formed on the lever 18. The pivot 41 connects the pawl member with one end of a rod 44 of which the other end is pivotally connected to the handle 38. A spring 45 connected to the rod 44 and to the plunger 42 exerts its tension so as to hold the pawl normally in engagement with the ratchet. When the handle 38 is moved to the rear against the tension of the spring 45, it first disengages the pawl from the ratchet and then engages a pin 46 on the lever 18 (see Fig. 1) and by further movement oscillates the lever about its fulcrum 19 thus retracting the presserfoot. The handle 38 is here shown as also mounted upon the fulcrum 19.

The plunger 42 is provided with an ear 47 against which a spring 48 contained in a socket in the lever 18 exerts its tension for the purpose of pressing the point of the pawl toward the ratchet. Means is provided, however, for automatically retracting the plunger 42 so as to disengage the pawl from the ratchet prior to the feeding movement of the carriage 25. For this purpose, the plunger is provided with a pin 49 which is adapted to be engaged by an arm 50 secured upon one end of a rock shaft 51 journaled in a bearing in the head 10. A shaft 51 is also provided with an

arm 52 on which is a roll 53 occupying the cam groove 39. Oscillatory movement imparted to the rock shaft 51 by means of the cam causes the arm 50 to retract the plunger 42 and so release the pawl. 70

It will be noted that, in the first instance in which the pawl is disengaged by movement of the handle 38, the pivot 40 remains stationary and constitutes the fulcrum about which the pawl swings, while in the latter case in which the pawl is automatically retracted, the pivot 41 remains stationary and constitutes the fulcrum during the operation of stitching a shoe. 75

It is desirable that the work should be free so that it may be quickly removed from the machine. This means that the needle and the awl must be clear of the work, the presserfoot 17 must be raised so as to release the work, and the needle thread, 85 which is indicated at *a*, should be free so that the work may be removed before the thread is cut. These conditions are all provided for in carrying out the present invention, and are brought about by retracting the presserfoot in still another way. Before proceeding to the explanation of the third way in which the presserfoot may be retracted, it will be necessary to describe the means herein shown for clamping 95 the needle thread at the proper intervals during the operation of the stitch-forming mechanism.

The needle thread *a* may be drawn from any suitable source of supply, preferably at the rear of the machine, and passed over a tension 54 and take-up rolls 55, 56 and 57 before passing through the looper 15. These elements may be of any desired construction and arrangement, and are supplemented by a pair of coöperative clamping members 60 and 61 which are as usual for the purpose of clamping the thread during the setting of a stitch. The clamping members are here shown as mounted upon the presserfoot 18, one of said members being in the form of a grooved roll and the other in the form of a slide movable toward and from the roll, and adapted to enter the groove to bind the thread. The slide 61 is mounted in guides 62 and is reciprocated by means of an arm 63 with which it has a pin and slot connection, the pin being indicated at 64 and the slot at 65. The slot is preferably curved so that it shall be concentric to the fulcrum 19 when the arm 63 is in the position shown. This enables the arm 63 to maintain the slide 61 in engagement with the roll 60 regardless of movement of the presserfoot lever about its fulcrum. 110

The arm 63 is affixed upon a rock shaft 77 which is journaled in a suitable bearing in the frame 10. Said rock shaft has a two arm lever 78 by which it may be actuated. One arm of the lever 78 extends down- 125 130

wardly in the form of a handle and is normally pressed in one direction by means of a spring 66 contained in a socket 79 formed upon the frame. The effect of the spring 66 is to force lever 78, rock shaft 77, arm 63, and slide 61 so as to bind the thread on the roll 60 with a yielding tension which is removed only when the shaft 77 is rocked in opposition to the spring 66. For this purpose, the other arm of the lever 78 is provided with a roll 67 which occupies a groove 68 formed in a cam member 69 on the shaft 11. The width of the groove 68 is greater than the diameter of the roll 67 and thus permits movement of the lever 78 independently of the member 69. The cam revolves in the direction indicated by the arrows in Figs. 1, 2 and 5, and is provided with inwardly projecting portions 70 and 71 formed on the outer wall of the groove 68. Although the spring 66 tends to force the roll 67 against the outer wall of the cam groove, the co-operative engagement of the two clamping members 60 61 prevents contact with the outer wall at all points excepting the portions 70 and 71 which effect the retraction of the slide 61 at the proper intervals. The function of the portion 70 is to release the needle thread at the time when a supply is being drawn for the succeeding stitch, and the function of the portion 71 is hereinafter explained.

Referring now to the third manner in which the presserfoot may be retracted, it should be noted that the plunger 42 carries a pivot stud 72 on which is mounted a finger 73. A spring 74 (see Figs. 3 and 4) is connected to the pin 49 and to the pin extending from the finger 73, and normally exerts its tension so as to hold the free end of the finger in engagement with the periphery of a cam disk 75 mounted upon the shaft 11. The drawings illustrate the machine in the position at which it should stop at the completion of a piece of work, and it may be presumed that suitable clutch-releasing and braking mechanism is provided for stopping the machine at this point. In this position, the awl 13 is in the work, the needle 12 is elevated clear of the work, the thread-clamping members are in co-operative engagement, and the presserfoot lever 18 is locked by means of the pawl 36. The several actuating elements are so related and timed that by turning the shaft 11 backward through approximately one-eighth of a revolution, the awl may be retracted from the work, the thread clamping members may be released and the presserfoot lever may be first released from the ratchet 37 and then retracted. In the periphery of the cam disk 75 against which the finger 73 is normally held is a recess the face 76 of which abuts against the free end of the finger 73 when the shaft is reversely rotated. Reverse rota-

tion of the shaft thus causes endwise movement of finger 73, and such movement causes the plunger 42 to slide in its guides 48 until the ear 47 strikes the lever 18. Further endwise movement of finger 73 is transmitted by the plunger 42 to the lever 18 to retract the presserfoot from the work. The sliding movement of the plunger relatively to the lever disengages the locking pawl 36 from the ratchet 37, thus unlocking the presserfoot-lever preparatory to retractive movement of the latter. At the same time the portion 71 on the cam 69 engages the roll 67 and thereby rocks the shaft 77 so as to disengage the thread-clamping members, and the crank 31 on the shaft 11 is turned sufficiently to retract the awl from the work. When the various parts are moved to the positions described, the work is entirely free and may be readily removed so that the needle thread *a* may be conveniently severed.

Having thus explained the nature of my said invention and described a way of constructing and using the same, although without attempting to set forth all of the forms in which it may be made or all of the modes of its use, I declare that what I claim is:—

1. In a machine of the character described, a presserfoot carrier, a hand lever, said carrier being arranged to be movable independently of said hand lever and said hand lever being arranged to be movable independently of said presserfoot carrier, means arranged to lock said presserfoot carrier, and means arranged to be operated by said hand lever to move said locking means to unlock said carrier, said carrier having an abutment arranged to be engaged by said hand lever to retract said carrier.

2. In a machine of the character described, a shaft, a work support, a presserfoot, a carrier for said presserfoot, a spring arranged to cause said presserfoot to coact with said work support, means arranged to lock said carrier, driven means arranged to act upon said locking means periodically to unlock said carrier when said machine is operating, a rotary driven member, a movable member arranged to be moved by said rotary driven member when said shaft is turned opposite to its operating direction, and means arranged to transmit such movement from said movable member to impart unlocking movement to said locking means and to impart retractive movement to said carrier, said movable member being ineffectual to operate said transmitting means when said shaft is turning in said operating direction.

3. In a machine of the character referred to, complementary stitch-forming mechanism, a presserfoot, a presserfoot-lever, a fulcrum for said lever, a stationary ratchet, a spring-pressed pawl on said presserfoot-lever for normally engaging said ratchet, automatic

means for periodically disengaging said pawl from said ratchet, and a thread-clamp in combination with means on the main shaft for simultaneously unlocking and lifting the presserfoot and unlocking the thread-clamp upon a reverse movement of said shaft.

4. In a machine of the character described, a presserfoot and lever therefor, a

- 10 fulcrum for said lever, normally coacting members for locking said lever, an abutment on said lever, a hand lever mounted on said fulcrum independently of said presserfoot lever, said hand lever being adapted to engage said abutment to move said presserfoot lever, and means operable by said hand lever for actuating one of said locking members to unlock said presserfoot lever.

5. In a machine of the character referred to, a shaft, stitch-forming mechanism driven thereby, a presserfoot, a presserfoot carrier, a fulcrum for said carrier, normally coacting ratchet and pawl members of which one is mounted on said carrier and the other on a fixture, and automatic means for periodically disengaging one of said coacting members from the other to unlock said carrier; in combination with a rotatable member having an operating surface, said member being driven by said shaft, and means adapted to be actuated by said surface, when the shaft is reversely rotated, to disengage one of said coacting locking members from the other and retract said presserfoot carrier.

6. In a machine of the character referred to, a shaft, stitch-forming mechanism driven thereby, a presserfoot, a presserfoot carrier, a fulcrum for said carrier, coacting ratchet and pawl members for locking said carrier, one of said locking members being mounted on said carrier and the other on a fixture, and one of them being spring-pressed into engagement with the other, automatic means for periodically disengaging one of said locking members from the other, and a thread clamp; in combination with means operative by reverse movement of said shaft for opening said thread clamp, and means likewise operative by said shaft for disengaging one of said locking members from the other and retracting said presserfoot carrier simultaneously with the aforesaid action of said thread clamp.

7. A sewing machine having, in combination, a rotary operating member, a movable presserfoot structure, a spring arranged to act on said presserfoot structure to press the latter against the work, a pivoted member arranged to coact with said operating member, a spring arranged to hold said pivoted member in position to coact with said operating member, said pivoted member being arranged to receive angular movement about

its pivot from said operating member when the latter is rotating in one direction, and to receive bodily movement from said operating member when the latter is rotating in the reverse direction, and means arranged to transmit such bodily movement of said pivoted member to said presserfoot structure to retract the latter.

8. A sewing machine having, in combination, a driving shaft, a work support, an arm bearing a presser foot for holding the work against the work support, and means for moving the presser foot away from the work support inactive during the normal operation of the machine but acting when the machine is turned backward including a link extending directly between the presser foot arm and the driving shaft and reciprocated by the driving shaft only when it is rotated in the reverse direction.

9. In a sole-sewing machine, the combination with a drive shaft, a work support, and a movable presser-foot, of a pivoted member, means connecting said pivoted member with said presser-foot, and operating means on said shaft constructed and arranged to move said pivoted member endwise upon reversal of said shaft, said connecting means being arranged to transmit such endwise movement to raise said presser foot.

10. In a sole-sewing machine, the combination with a drive shaft, a work support, and a movable presser foot, of an arm pivoted on said presser-foot, and operating means on said shaft constructed and arranged to move said arm endwise upon reversal of said shaft to raise said presser-foot, said operating means swinging said arm on its pivot during the normal rotation of said shaft.

11. In a machine of the character described, a shaft, stitch-forming mechanism arranged to be operated by said shaft when rotating in one direction, a work rest, a work-engaging member arranged to coact with said work rest to clamp the work, and means arranged to be operated by said shaft when rotated in the reverse direction to retract said work-engaging member, said retracting means being arranged to be ineffective for the purpose stated when said shaft is rotated in the first-mentioned direction.

12. In a machine of the character described, a shaft, stitch-forming mechanism arranged to be operated by said shaft when rotating in one direction, a work rest, a work-engaging member arranged to coact with said work rest to clamp the work, means arranged to lock said member against unclamping movement, and means arranged to be operated by said shaft to unlock said locking means and retract said work-engaging member only when said shaft is rotated in the reverse direction.

13. In a machine of the character described, a shaft, stitch-forming mechanism arranged to be operated by said shaft when rotating in one direction, work-engaging means arranged to clamp the work, and means arranged to be operated by said shaft to act on said clamping means to release the work only when said shaft is rotated in the reverse direction. 5
14. In a machine of the character described, a shaft, stitch-forming mechanism arranged to be operated by said shaft when rotating in one direction, thread-clamping means arranged to be operated by said shaft to clamp and release the thread, work-engaging means arranged to clamp the work, and means arranged to be operated by said shaft to act on said clamping means only when said shaft is rotated in the reverse direction to unclamp the work, said unclamping means being arranged to be effective for the purpose stated when the thread is released by said thread-clamping means. 10
15. In a machine of the character described, a shaft, stitch-forming mechanism arranged to be operated by said shaft rotating in one direction, a presserfoot, and means arranged to be operated by said shaft to retract said presserfoot only when said shaft is rotated in the reverse direction. 25 30
16. In a machine of the character described, a shaft, stitch-forming mechanism arranged to be operated by said shaft turning in one direction, a presserfoot, means arranged to lock said presserfoot, and means arranged to be operated by said shaft to act on said locking means to unlock said presserfoot only when said shaft is rotated in the reverse direction. 35

In testimony whereof I have affixed my 40
signature, in presence of two witnesses.

HARRIE A. BALLARD.
